FOLDING FAN

Rosalia Elisabeth Spisak, Chicago, Ill.

Application January 22, 1940, Serial No. 314,918

1 Claim. (Cl. 230—268)

This invention relates to a novel and improved folding fan for general use.

The main object of this invention is to provide a folding fan which is artistically attractive and of suitable size to be used, in the absence of a mechanical fan, at any place or occasion.

Another object of the invention is to save space, i. e., so to construct the folding fan that, when not in use, it may be carried in a pocket or a handbag.

A further object of the invention is to provide a folding fan which can be used as an advertising medium and premium.

A still further object of the invention is to provide a device of the character described which will be simple in construction and assembly, which may be produced along lines convenient for low cost manufacture and which will, at the same time, be highly efficient for carrying out the purposes for which it is designed.

With the foregoing and other objects in view, which will appear as the description proceeds, the invention consists in certain novel features in construction, arrangement and combination of parts herein more fully described, illustrated in the accompanying drawing, and particularly pointed out in the appended claim, it being understood that various changes in the form, proportion, size, color, and minor details of the structure may be made without departing from the spirit or sacrificing any of the advantages of the invention.

For the purpose of facilitating an understanding of the invention, I have illustrated in the accompanying drawing a preferred embodiment thereof, from an inspection of which, when considered in connection with the following description, the invention, its mode of construction, assembly and operation, and many of its advantages should be readily understood and appreciated.

Referring to the drawing, in which same characters of reference are employed to indicate corresponding or similar parts throughout the several figures of the drawing:

Fig. 1 is a top plan view of the fan.

Fig. 2 is a top plan view of the fan in folded position.

Fig. 3 is a sectional view on line 3—3 of Fig. 2.

Fig. 4 is a section on line 4—4 of Fig. 1.

Fig. 5 is a section on line 5—5 of Fig. 1.

Fig. 6 is a section on line 6—6 of Fig. 1.

Referring to the drawing more specifically by characters of reference, the folding fan consists essentially of a fan blade 1, which is divided into

axial symmetrical portions 2, and 3, respectively, the axis of symmetry is represented by the tensional crease 4, said tensional crease 4, is so shaped that it possesses a very marked springy effect, which normally tends to fold the two symmetrical portions 2, and 3, around the axis 4, into an angular position relative to each other, which requires a force to maintain the two portions in open position as a fan blade, but force is also required to keep the two portions 2, and 3, respectively, tightly folded upon each other.

The force necessary to keep the two symmetrical portions 2, and 3, respectively, in an open position, or tightly folded when not in use, is effected by means of a suitable T-shaped handle 5, having a top flange 6, and a web 7; the top flange 6, has two suitable end portions 8, and 9, respectively. The portion 8, is pivotally secured to the portion 2, at a suitable place by means of the eyelet 10.

The slot 11, is so disposed within the portion 3, that when the two symmetrical portions 2, and 3, are in open position, the free end 9, of the top flange 6, of the handle 5, engages the said slot 11, the outer edge 14, of which is slightly elevated to permit an easier sliding of the said free end 9, enabling the fan to be used.

When the fan is not in use, the handle 5, may be rotated around the eyelet 10, in such a way, that the free end 9, disengages the slot 11; the two symmetrical portions 2, and 3, respectively, fold around the axis 4, and form an angle with each other, said two portions 2, and 3, respectively, are now held together by hand, covering each other completely; the slots 12, and 13, respectively, which are also axial symmetrically arranged, form a composite slot 17, which engages the free end 9, of the top flange 6, of the handle 5.

To facilitate the engaging and disengaging of the free end 9, of top flange 6, with the said composite slot 17, the outer edges 15, 16, of the slots 12, and 13, respectively, are slightly elevated anticlockwise from the main plan.

Fig. 1 shows that when the fan is in open position, the handle 5, serves as a grip, while in Fig. 2, where the fan is shown in folded position, the handle 5, rests upon the portion 2, and serves as a spring to retain the portions 2, and 3, respectively, together, thereby reducing storage space.

For manufacturing purposes, any suitable shape, material and coloring may be used, such as artistic designs or advertising.

What I claim as new and desire to secure by Letters Patent of the United States is:

A folding fan comprising a fan blade and a T- 55

shaped handle having a top flange and a web, a tensional crease at the middle of said fan blade, dividing the same into two equal axially symmetrical portions, one of said portions being pivotally connected at a suitable place to one end of the top flange of said handle, said axially symmetrical portions of the fan blade having axially symmetrical slots disposed at suitable places to cover each other and receive the free end of the top flange of said handle when the fan blade is folded

along said crease with the handle on the outside, thereby retaining the two axially symmetrical portions of said fan blade in folded position, said fan blade being further provided in the other of said portions with a slot positioned at one side of 5 said crease to receive the free end of the top flange of the handle when the blade is in open position to thereby retain the two portions of the blade in open position.
